FLUID FUEL BURNER

Original Filed Dec. 27, 1932

UNITED STATES PATENT OFFICE

2,015,048

FLUID FUEL BURNER

Walter W. Williams, Philip A. Celander, and Oliver Earl Nesmith, Bloomington, Ill.; said Celander and said Nesmith assigns to Williams Oil-O-Matic Heating Corporation, Bloomington, Ill., a corporation of Illinois

Original application December 27, 1932, Serial No. 648,966. Divided and this application October 4, 1933, Serial No. 692,096

1 Claim. (Cl. 158—36.5)

This invention relates to improvements in electrically operated fluid fuel burners, more particularly to the domestic type which is particularly adapted for installation with the heating plants of homes and buildings, and is a division of Serial Number 648,966, filed December 27, 1932.

It is an object of this invention to reduce the noise of operation, improve the construction of the fluid fuel discharging means, and provide a simple and positive control for the supply of fluid fuel operated by the actuation of the burner mechanism.

With these and other objects in view, reference is made to the accompanying sheet of drawings which illustrates a preferred form of this invention with the understanding that minor detail changes may be made therein without departing from the scope thereof.

In the drawing:

Figure 1 is a view in side elevation of a commercial type of domestic fluid fuel burner with parts broken away, illustrating the draft pipe, nozzle, a portion of the fan housing, and a fuel discharge chamber in section.

Figure 2 is a fragmentary enlarged detail view of the fuel discharge chamber including the mounting of the oil pipe.

Figure 3 is an enlarged detail view partly in section and partly in elevation of the nozzle and attached fuel and air delivery pipes as illustrated in Figure 2.

Figure 4 is a view in transverse section taken on the lines 4—4 of Figure 3 looking in the direction of the arrows.

In the embodiment of this invention as illustrated, the base 1 supports an integral fan blower casing or housing 2 having an extension for receiving and mounting an electric motor, not shown. The motor is provided with a driving shaft for operating an oil pump 3 and also operating a fan blower. The driving shaft is extended through the opposite side of the motor for operating a compression pump and metering pump mounted, not shown. The general construction and operation of the pressure pump and metering pump is of the type disclosed in the W. W. Williams Patent No. 1,451,798, granted April 17, 1923.

Mounted upon the base 1 and extending from the fan housing 2 a draft pipe 4 is provided. Fuel is delivered through the pipe 5 centrally mounted within the draft pipe and terminating in a nozzle 6 adjacent the open end of the draft pipe 4 and continuing in the opposite direction through

the lower part of the housing and communicating with a float chamber 7 which in turn communicates by the pipe 8 with the pressure pump. This construction in general is disclosed in W. W. Williams' prior Patent No. 1,831,277, granted November 10, 1931, upon a fluid fuel burner construction. The pipe 5 supports electrodes 9 terminating a short distance in advance of nozzle 6.

When the motor is operating, air is drawn in through the muffler and intake to the pressure pump and at the same time oil is metered into the intake of the pressure pump through the metering pump and both air and oil under pressure are delivered from the pressure pump through the pipe 8 to the float valve casing 7, as shown in Figure 1.

The float valve casing 7 is shown in detail in Figure 1. As heretofore stated, fuel is delivered from the float valve casing 7 through the pipe 5 and is discharged at the open end of the draft pipe 4 through the nozzle 6. As shown in Figure 1, the pipe 5 is threaded at one end to the float valve casing and mounts the nozzle 6 at the other end, which is held concentric with the axis of the draft pipe by the spider arms 9^a mounted on the pipe 5 adjacent to the nozzle.

As disclosed in W. W. Williams' prior Patent No. 1,831,277, dated November 10, 1931, the air and oil entering the float valve casing 7 separate and, as the level of the oil rises, it causes the float 10 to ascend and uncover a port, not shown, in the pipe 11 threaded into the block 12, which also mounts the pivot 13 of the float valve. An oil pipe 14 of less diameter than the pipe 5 is screw-threaded into the block 12 and communicates with the pipe 11. The oil pipe 14 mounts at the free end what is termed an air spiral, which includes a square casing 15 with beveled corners, adapted to be snugly received within a center cylindrical bore 16 of the nozzle 6, as shown in Figures 3 and 4. The oil pipe 14 is arranged concentrically within the pipe 5, so that if the float 10 uncovers the port in the pipe 11, the pressure of the air above the level of the oil will force the oil through pipes 11 and 14 and at the same time air is delivered through the space between the interior of the pipe 5 and exterior of the pipe 14 to the nozzle. The air spiral or casing 15 is constructed in the manner disclosed in W. W. Williams' prior pending application, Serial No. 540,416, filed May 27, 1931, now Patent No. 1,934,755, issued November 14, 1933, omitting the screw-threaded portion on the air spiral engaging corresponding threads within the nozzle. The nozzle is provided with a center dis-

charge orifice 17 and the outer end of the casing 15 is provided with a transverse wall peripherally beveled to engage the interior end closure of the nozzle 6 and form a tip chamber between this end wall and the nozzle wall. The square sides of the casing 15 are provided with grooved air passages 18 tangential to the tip chamber. The interior 19 of the casing 15 at its open end is screw-threaded upon the pipe 14 and at its closed end is provided with a plurality of angular passages 20, opening into each of the grooved air passages 18. The transverse end wall of the square casing 15 is provided with a conical projection 21, which is concentric with the axis of the casing 15 and discharge orifice 17 with the apex terminating flush with the nozzle discharge orifice, so that the sides of the cone are spaced apart and are substantially parallel to the portion of the nozzle closure tapering away from the nozzle orifice 17. The nozzle 6 is provided with a screw threaded connection upon the pipe 5.

The block 12 is mounted upon a pin 22 carried upon that part of the blower housing 2 which forms an end closure for the float valve casing 7. This portion of the blower housing is extended below the pin 22 and is provided with a recess 23 through which the oil pipe 14 passes. The oil pipe 14 is provided with an adjustable shoulder or stop 24 and a coil spring 25 is placed about the oil pipe 14 with one end received within the recess 23 and the other end in engagement with the shoulder 24. The shoulder 24 is so adjusted that the coil spring 25 exerts a continuous pressure upon the oil pipe in the direction of the nozzle, whereby not only is the block 12 held in position on the pin 22 but the square housing 15 is always held against the closure of the nozzle 6.

This construction not only obviates the necessity of a stuffing box or packing gland between the pipe 11 and the oil pipe 14, as was necessary in the construction disclosed in the applicant's, Walter W. Williams' Patent No. 1,831,277, but

also provides a structure in which no leak can occur. The air spiral or square casing 15 makes a very close fit with the walls of the nozzle chamber 16 and is held in position by the spring 25, with the conical projection 21 directly in the center of the discharged orifice 17 of the nozzle. It has been found that it is almost impossible to exactly center the apex of such a conical projection upon an air spiral when the air spiral is screw-threaded into the nozzle, as disclosed in the said prior copending application No. 540,-416, and in the improved construction illustrated in this application, the continual heating and cooling of the outside shell of the nozzle 6, causing contraction and expansion, does not change the relation of the conical projection 21 to the discharge orifice 17, as such movement is compensated for by the coil spring 25.

What we claim is:

Means for mounting one end of a fuel pipe in a fluid fuel burner mechanism having a burner nozzle having a central discharge opening and a pump for delivering fuel and air through said nozzle, including a float chamber receiving the fuel and air under pressure before it is delivered to the nozzle, an air pipe leading from the chamber to the nozzle, and a fuel pipe leading from the chamber passing centrally through said air pipe mounting a fuel spiral forming one end of the fuel pipe freely slidably axially within the nozzle, a perforated bracket provided upon the interior of the chamber slidably supporting the other end of the fuel pipe, a block carried on the end of the fuel pipe supporting an angular extension of the fuel pipe, a pin extending from said bracket slidably supporting said block, an abutment upon the fuel pipe, and a spring about said fuel pipe between said abutment and said bracket to maintain the fuel spiral in contact with the nozzle and the block in position upon its pin.
